SHOWER HEAD

Wilfred Rush Thornton, Toronto, Ontario,
Canada

Application July 28, 1947, Serial No. 764,066

3 Claims. (Cl. 299—126)

1

This invention relates to a shower head.

Shower heads have been provided in the past. To my knowledge, however, none of them are capable of producing an extremely fine spray. There is considerable need for a shower head which is capable of producing such a fine spray in hospital work. Many hospital patients have extremely sensitive skin and it is impossible to use the spray or shower from the conventional shower head on them. I have invented a shower head which is capable of producing an extremely fine spray and which will not irritate the most sensitive skin. The head is also capable of producing quite a coarse and invigorating spray if desired.

It is, therefore, an object of the present invention to produce a shower head spray which is capable of emitting an extremely fine spray which will not irritate the most sensitive skin.

It is a further object of the invention to produce a shower head having the above mentioned characteristics which can be adjusted to produce a relatively coarse and invigorating spray if desired.

It is a further object of the invention to produce a shower head having the above characteristics which is rugged and which is cheap to manufacture.

With these and other objects in view the shower head of this invention generally comprises a nozzle having a valve chamber adapted to permit the flow of a fluid therethrough and to partially break it up into a spray and a means for connecting the nozzle to a water supply. Flow through the chamber from the water supply is controlled by means of a valve adjustable within the chamber. The water, on leaving the nozzle, is directed against a rotatably mounted impeller. The force of the water causes the impeller to rotate and the rotating motion of the impeller breaks the fluid up into a fine spray. The amount of water passing and the consistency of the spray are controlled by adjusting the valve within the valve chamber.

The invention will be clearly understood after reference to the following detailed specification taken in conjunction with the drawings.

In the drawings:

Figure 1 is a sectional view taken through a shower head of this invention.

Figure 2 is a perspective view of the form of valve used in Figure 1.

Figure 3 is a perspective view showing the impeller.

Figure 4 is a plan view of the impeller.

Figure 5 is a partial section showing a further

2

adjustment of the valve within the valve chamber.

Referring to the drawings and especially to Figure 1, A represents a shower head of this invention which in general comprises a nozzle B, having a valve chamber 10 therein and a valve 11 adjustable within the chamber, and a cup-shaped member C, adjustable with respect to the nozzle B and having means in connection therewith for the purposes of adjusting the valve 11 within the chamber 10.

The nozzle B comprises a body portion 12 which, in the embodiment shown, has an exterior thread 13 whereby the nozzle can be connected to a water tap or the like by means of a threaded portion 14 in the connector 15 so that the valve chamber 10 communicates with the tap opening. The valve chamber 10 is formed with a conical seat 16 at its lower end, and the valve 11 has a head 17 with a conical portion 18 at its lower extremity adapted to snugly sit in the seat 16 to prevent the flow of water when it is so adjusted. This adjustment will be described in detail later.

25 The orifice of the nozzle is preferably flared outwardly as at 19 to direct the flow of water against an impeller member 20, which is rotatably mounted in advance of the nozzle. This will be described later.

30 The head 17 of the valve 11 is substantially triangular in cross section and is designed to fit loosely within the valve chamber 10 so as to permit a free flow of water therethrough. A pin portion 21 projects from the head 17 and is adapted to extend beyond the valve chamber opening 22 and nozzle orifice to bear against a bracket 23.

35 The bracket 23 is rigidly mounted on the inner wall 24 of cup-shaped member C, and member C is in turn adjustably carried by a nut 25. The nut 25 is adjustable on the threaded exterior portion 13 of the body of the nozzle body 12 to adjust the position of the cup-shaped member C. It will be apparent that by adjusting the nut 25 on the threaded portion of the nozzle 12, the valve 11 can be adjusted longitudinally within valve chamber 10 from a completely closed position, in which the conical portion 18 of the valve head 17 is seated on the valve seat 16, to various opened positions in which various amounts of flow are permitted to pass through the nozzle.

40 The pin 21 has a bead 26. This bead is designed to partially break the water into a spray as it passes through the nozzle and is so designed that it can pass through the valve chamber

opening 22. In the embodiment shown, the bead is conically shaped on either side of a central band.

The impeller 20, shown in detail in Figure 3, is formed from any suitable metal and, in the embodiment shown, has an annular wall portion 27 and two vanes 28. A bar 29 extends between the walls 27 and the impeller is suitably journaled within the bracket 23 by means of pin 30 which passes through said bar 29. As mentioned above, the orifice 19 of the nozzle is designed to direct the flow of water against the impeller walls 27 and blades 28. This causes the impeller to rotate and to emit the water in a fine spray. I have found that a more satisfactory nozzle action is obtained if ventilating openings 31 and 32 are formed in the nozzle B, in the region of the flared area 19, and in the cup member C respectively.

In use, water coming from the tap travels through the valve chamber 10 past the loosely fitting valve head 17 through the valve chamber opening 22 and is directed by the nozzle orifices 19 against the impeller whereby the impeller is caused to rotate. The water, on passing the bead 26 on the valve 11, is partially broken into a spray. On passing through the impeller, however, the water is further broken up into an extremely fine spray.

The fineness of the spray can be readily adjusted by varying the position of the valve 11 within the valve chamber. As indicated above, this can be done by rotating the cup member C which is rigidly secured to the nut 25. As the cup is rotated, the nut 25 screws on the threaded portion, whereby bracket 23 bears against the valve pin 21 to vary the position of the valve within the nozzle. When the valve is in the position shown in Figure 1, a relatively fine spray is produced. An extremely fine spray can be produced by positioning the valve such that the bead 26 lies within the valve opening 22 as shown in Figure 5. A coarse pulsating spray is produced when the bead 26 is positioned in the orifice 19 of the nozzle, as shown in the dotted line position in Figure 5.

From the above, it will be apparent that I have disclosed a shower head which accomplishes the purposes of this invention. With this head it is possible to produce a very fine spray and a coarse pulsating spray. The head is also cheap to manufacture and is extremely rugged.

Changes and modifications in the embodiment of the invention shown will be apparent to those skilled in the art. It is, therefore, not intended that the foregoing specification should be read in a limiting sense except for the limitations expressed in the following claims.

What I claim as my invention is:

1. A shower head comprising a nozzle adapted for connection to a fluid supply, an impeller rotatably mounted below said nozzle, said impeller having an annular wall portion and a plurality of vanes depending therefrom, said nozzle having a valve chamber, and a valve adjustable within the chamber to vary the flow of water therethrough, said valve having a head with a cross section substantially smaller than the cross section of the valve chamber and a pin extending from said head and adapted to project through the orifice of said nozzle, said valve pin having a bead thereon

adapted to partially break the water up into a spray as it passes through said nozzle, means adjustable with respect to the nozzle and adapted to bear against the projecting portion of said pin to adjust the position of said valve within the valve chamber and vary the amount and characteristics of the flow therethrough, said nozzle having an orifice adapted to direct the flow of water against the inner surfaces of said wall portion and of said vanes of said impeller whereby the impeller is caused to rotate and further break up the water into a finer spray.

2. A shower head comprising a nozzle adapted for connection to a fluid supply, a cup-shaped member, said nozzle having an exterior threaded portion adapted to receive the base of said cup-shaped member in threaded engagement, said nozzle having a valve chamber, and a valve adjustable therein adapted to vary the flow through 15 said nozzle and partially break it up into a spray, said valve having a portion which is adapted to project through the orifice of said nozzle, means exterior of said valve chamber for adjusting said valve within said valve chamber, said means including a bracket rigidly secured to said cup and adapted to bear against the projecting portion of said valve whereby the position of the valve can be varied within the valve chamber as the cup is threaded on the nozzle, an impeller rotatably mounted within said cup member below said nozzle, said impeller having an annular wall portion and a plurality of vanes depending therefrom, said nozzle having an orifice adapted to direct the flow of water against the inner surfaces of said 25 wall portion and of said vanes of said impeller whereby the impeller is caused to rotate and further break up the water into a fine spray and project it beyond said cup-shaped member.

3. A shower head as claimed in claim 2 in which 30 said cup member has at least one air vent adjacent its base and in which said nozzle has at least one air duct extending from the exterior to the interior of the discharge orifice.
